UNITED STATES PATENT OFFICE.

REINHOLD H. WAPPLER, OF NEW YORK, N. Y.

MEDICAL PUMP.

SPECIFICATION forming part of Letters Patent No. 634,678, dated October 10, 1899.

Application filed May 26, 1899. Serial No. 718,342. (No model.)

To all whom it may concern:

Be it known that I, REINHOLD H. WAPPLER, a citizen of the United States, residing in the city and State of New York, have invented 5 an Improvement in Medical Pumps, of which the following is a specification.

This invention relates to an oscillating pump, preferably driven by an electric motor, and in connection with the cylinder and piston there is a movable valve-plate with tubular nipple-handles and flexible connections by which an alternation of pressure and suction can be applied to any portion of the body, and the action can be changed by moving the valve-plate without changing the 15 tubular connections to the parts treated.

By the present improvement an alternation of pressure and suction or a continued pressure or suction can be applied by the flexible 20 connections to any part of the body. This is available in treating catarrh by atmospheric action or by the injection of medicinal substances or vapors or the withdrawal of effete matter, and in cases of deafness the 25 apparatus can be used for energizing the parts of the ear by an alternation of pressure and suction or by the injection into the ear of any medicinal material or the withdrawal from the ear of substances that may have 30 been inserted. A spray can also be employed by this apparatus, or atmosphere charged with vapor can be projected into or against the affected parts.

This improvement is also available for massage treatment, in which alternation of pressure and suction, similar to cupping, can be employed or a continuous suction made use of or a continuous pressure, and this may be used in cases of rheumatism or in the treatment 35 of boils, abscesses, or other abnormal conditions of the parts or tissues.

In the drawings, Figure 1 is an elevation of the apparatus endwise of the armature. Fig. 2 represents the face of the valve-plate. 45 Fig. 3 is a plan view illustrating one end of the motor and a section of the air-cylinder and adjacent parts, and Fig. 4 shows the face of the plate against which the oscillating cylinder rests.

50 The shaft A is revolved by suitable power. I have represented the same as the armature-

shaft in an electric motor A', and this is mounted upon a base B, which may contain a rheostat B², by which the force of the current and the speed of rotation can be regulated, and at C are conductors to the source of electric energy, and, if desired, conductors D may be led away from one head of the electric motor for use in any desired manner in applying an electric current to the body 60 through a transformer B' or by direct action or to a cauterizer or other surgical appliance, the apparatus being made with reference to the electrical or pneumatic appliances known or used in medical or surgical operations. 65 My said improvement, however, relates to the pump and appliances hereinafter described.

The cylinder E is mounted on the pivot or trunnion at 3, so that it can oscillate by the action of the piston-rod F to the crank G upon 70 the shaft A, which is rotated electrically or otherwise at the desired speed, and as it rotates the piston-rod and piston are reciprocated and the cylinder E oscillated upon its trunnion or pivot.

75 It is advantageous to employ a piston F' sufficiently long to oscillate the cylinder, as the piston and piston-rod receive their motion from the crank. The plate 4 is connected to the cylinder E and lies against the fixed plate 5 on the face thereof, and the trunnion 3 of the plate 4 passes through the plate 5 and through an oblong hole in the valve-plate H on the back of the plate 5, and a spring 80 around the end of the trunnion 3 presses the 85 plates 4 and H together and to opposite sides of the fixed plate 5, the plate H being pivoted to 5 by screw 6. A screw in the end of the trunnion 3 applies tension to the spring 20. There is a passage-way or port 13 from the 90 cylinder E through the same and the plate 4 to the surface of the plate 4, and in the fixed plate 5 there are two holes 12 and 14 and on the rear of this plate a slight projection. With the movement of the piston the port 13 95 moves between the ports 12 and 14, agreeing therewith in its respective positions.

The valve-plate H, pivoted at 6, is provided with two nipples 7 and 8, that are adapted to receive the flexible tubes I K. In this valve-plate H are three small holes 15 to fit over a 100 projection on the rear of the plate 5, which

holes determine the several positions of the valve-plate H and hold the same. Through this valve-plate H is a hole 9, and into the same an elongated hole 11 and a hole 10, the 5 holes 11 and 10 meeting the holes extending through and from the nipples 7 and 8, and the elongated hole 11 is of sufficient size to cover the holes 12 and 14 of the plate 5.

There are three positions for the valve-plate 10 H in relation to the fixed plate 5, and Figs. 1 and 2 show the first position, in which the holes 10 and 14 agree and 11 and 12 agree. In this position the air is drawn through the vessel L and tube I and forced out by the 15 tube K. In the second position of the valve-plate H the elongated opening 11 covers both openings 12 and 14, and in the movement of the piston and plate 4 there is alternate suction and pressure through the tube K and 20 other parts are unaffected. In the third position of the valve-plate H the opening 11 agrees with the hole 14 and the hole 12 with the hole 9 through the valve-plate, and in this 25 position there is a continuous suction action through the pipe K and nipple 8. If the direction of rotation is reversed with the parts in the first position, as shown, then the air is drawn in by the tube K and forced out through the tube I as the piston reciprocates and the 30 cylinder oscillates.

I have represented a jar L for containing a medicated liquid connected to the tube I, so that atmosphere can be drawn through such liquid into the cylinder E and then expelled 35 by the tube K to the place where it is made use of medicinally, and by swinging the valve-plate H in one direction or the other the action can be changed, so as to produce an alternate suction and expulsion of air through 40 the tube K.

I do not limit myself to any particular power made use of for rotating the crank-shaft; but it is generally advantageous to employ the rheostat at B³, so that the speed 45 of rotation can be regulated according to the current and the apparatus can be made use of in medical or surgical operations generally.

Any desired provision may be made for lubricating the parts, and a screw is provided 50 at 16 upon the cylinder-head that may be turned to allow more or less air to pass into and out of the cylinder, and thereby the pneumatic action through the tubes I K will be regulated.

55 I claim as my invention—

1. The combination with an oscillating cylinder, piston, piston-rod and crank, of a stationary plate upon which the cylinder is pivoted, ports through the said plate, a valve-plate 60 and pivot and tubes through the same and tubular nipples for the reception of tubular connections, said valve-plate being pivoted so as to be changed in position to regulate the suction or compression action through 65 the respective tubes, substantially as set forth.

2. The combination with an electric motor and rheostat for regulating the electric current, of a crank upon the armature-shaft, a connecting-rod and piston, an oscillating cylinder and a stationary plate upon which the cylinder is pivoted, a valve-plate pivoted upon the stationary plate and having tubular nipples thereon for flexible connections and tubular ports acting in connection with the stationary plate for applying a suction or compression action through the respective tubes for medical or other purposes, substantially as set forth. 70

3: The combination with an electric motor, 80 an oscillating cylinder, piston, piston-rod and crank on the armature-shaft, of a stationary plate upon which the cylinder is pivoted, ports through said plate, a valve-plate pivoted to the stationary plate and provided with tubular nipples, a hole through the plate and holes in the surface of the plate connecting with the holes from the tubular nipples, said valve-plate being adapted to be changed in 85 position to regulate the suction or compression action through the respective tubes, substantially as set forth. 90

4. The combination with an electric motor, an oscillating cylinder, piston, piston-rod and a crank upon the armature-shaft, of a stationary plate having two ports through the same, a plate through which and the cylinder there is a port, said plate having a trunnion passing through the stationary plate and extending rearward, a valve-plate pivoted to the stationary plate and having an elongated mortise for the trunnion of the cylinder, a spring upon the said trunnion and means for applying tension to the same whereby the surfaces of the valve-plate and the cylinder-plate 105 are held against the surfaces of the fixed plate, tubular nipples connected to the valve-plate and having their openings prolonged into the said plate and holes in the surface of the plate adjoining the same and a hole through 110 the plate whereby the valve-plate is adapted to occupy several positions to regulate the suction or compression action through the respective tubes, substantially as set forth. 100

5. The combination with an electric motor, 115 an oscillating cylinder, piston, piston-rod and a crank upon the armature-shaft, of a stationary plate having two ports through the same, a plate through which and the cylinder there is a port, said plate having a trunnion 120 passing through the stationary plate and extending rearward, a valve-plate pivoted to the stationary plate and having an elongated mortise for the trunnion of the cylinder, a spring upon the said trunnion and means for applying tension to the same whereby the surfaces of the valve-plate and the cylinder-plate are held against the surfaces of the fixed plate, 125 tubular nipples connected to the valve-plate and having their openings prolonged into the said plate and holes in the surface of the plate adjoining the same and a hole through 130

the plate, the tubes K and I connected to the tubular nipples, a vessel L to which the tube I is connected whereby the valve-plate is adapted to occupy several positions to regulate the suction or compression action through the respective tubes, and also whereby in one position of the valve-plate air may be drawn through the tube K and forced through the

tube I and the vessel L or in the reverse direction, substantially as set forth.

Signed by me this 20th day of May, 1899.

REINHOLD H. WAPPLER.
